MOISTUREPROOFING

Francis P. McColl, St. Andrews, New Brunswick,
Canada; Mary Pamelia McColl executrix of
said Francis P. McColl, deceased

Original application November 7, 1933, Serial No.
697,011. Divided and this application Decem-
ber 3, 1934, Serial No. 755,737

7 Claims. (Cl. 229—3.5)

My invention relates to improvements in laminating or coating paper, card, or other material, or containers of the same by cellulose or other substantially moisture-proof materials, preferably transparent, and has especially to do with, and is illustrated in the accompanying drawings in its application to the moisture-proofing and formation of containers such as paper cans, and more particularly, has reference to means for laminating sheets of material for lining, and covering in some instances, the exterior as well as the interior of such container, thus providing an inner or outer covering, coating or laminating of substantially non-porous, and preferably transparent material, and in some instances, the container is provided between the body of the container and the covering with a sheet of material such as paper, sometimes colored, producing the effect of enameling, and involves the sealing, fusing, or hermetical binding of the walls of the container and laminations where the same join, such as at the seams or laps, thus in most instances forming a complete unitary, substantially moisture-proof container within an outer more or less moisture-proof shell or container, and the present application is a division of my application 697,011, filed November 7, 1933.

Referring to the accompanying drawings, I have diagrammatically illustrated in Figure 1, in side elevation, a suitable arrangement of mechanism for laminating card or paper stock with cellulose, or similar material;

Figure 2 shows a strip of card or paper in the process of being laminated;

Figure 3 shows a laminated blank of a form adapted for a wall of a conical container;

Figure 4 illustrates in perspective an arrangement of body material, label and linings for straight winding;

Figure 5 is a perspective view of the body of a can made with a composite strip arranged substantially as shown in Figure 4;

Figure 6 illustrates in plan view a built-up or composite strip for forming into the cylinder body portion of a container;

Figure 7 is a sectional view through one end portion of a cylindrical vessel lined and covered as per the present invention.

Figure 8 is a sectional view through one of the heads of such container before application thereto.

Figure 9 is a sectional view illustrating the initial association of the container of Figure 7 and the head of Figure 8.

Figure 10 is a similar view illustrating the head locked in place.

Figure 11 is an edge view of a preformed strip going into the making of the container of Figure 7; and

Figure 12 is a plan view of a blank illustrating

the manner of formation of the preformed strip of Figure 11.

Referring now more particularly to Figure 1, the same illustrates rolls 6 and 7 of very thin cellulose or other suitable non-porous, preferably transparent material, and 8 indicates a similar roll of paper stock or card to be laminated or covered with the transparent, non-porous material, 9, 10, indicate troughs of methol cellosolve, a solvent for the cellulose, containing rosin, gum, acetate, and sometimes other ingredients, which may be used as a solvent, cement or adhesive for sticking or fastening the cellulose sheet to the card or board, and to itself where the same overlaps. Such a solution may be made up as follows: heavy acetate, 75 parts and methol cellosolve 50 parts, to which may be added 5 parts of gum or 73 parts of acetate may be used to 10 parts of a suitable gum with 15 parts methol cellosolve. In any case, the adhesive or binder preferably is such that it has some dissolving effect so that the margin of the cellulose where overlapped is actually united, bonded and hermetically attached, thus forming an integral or continuous piece, while at the same time it serves as a filler and an adhesive.

11, 12 indicate rollers upon shafts 13, 14 adapted to rotate within the troughs 9, 10, and in the solution referred to, said solution being indicated by the reference characters 15, 16 and 17, 18 indicate rollers similarly mounted and contacting with the partially immersed rollers 11, 12, as shown, to pick up and take the adhesive, and pass it to the under-surface of the strips or webs of cellulose, 19, 20, as the same pass over the rollers as shown, and beneath the rollers 21, 22. In passing between said rollers last mentioned, the adhesive covered faces of the strips of cellulose, 19, 20 pass against, the strip of card or board 23, as shown, the cellulose being thereby applied uniformly, flatly and smoothly upon the card fastening thereto.

By reference now more particularly to Figure 2, it will be observed that the width of the cellulose strips is less than the width of the card or paper 23, and that the inner margins of the cellulose strips at opposite faces of the card overlap (with the card or board between) as shown at Figure 2, while the outer margins thereof at opposite faces and opposite sides of the card or board extend beyond the board or card.

Referring now again to Figure 1, I have indicated at 24, a suitable folder or seamer of any desirable shape such as is well-known in the paper folding arts, so that as the composite strip 25 feeds through the same with the marginal portion 19' and 20' of cellulose extending, said marginal portions are preferably folded or laid over the card or board on the opposite faces thereof while the composite strip is pressed be-

tween the rollers 26, 27, and pressed beneath the rollers 28, 29, upon the roller 26, passing downwardly beneath the roller 30 to the heater 31 of any suitable form, where the composite strip 5 is finally dried and set, after which it passes over the roller 32, and is wound upon the take-up roll 33, which may now be used for forming cylindrical containers such as paper cans, and, of course it will be readily understood that tin-plate or other material may be used instead of card or paper, if desired.

When a tapered container is desired, a blank is cut and formed, substantially as shown in Figure 3, instead of having straight parallel sides as shown in Figure 2. Such a container is formed by rolling one end of the blank shown in Figure 3 within the other, until the lateral margins overlap, whereupon the inner and outer walls of the cone thus formed will be found to be entirely covered with the transparent material, and the overlapping margins may then be cemented or bonded together, thus forming a tapered or cone-like tube, having a substantially continuous inner and outer wall or lamination of substantially water-proof and transparent material.

As an adhesive, I may dissolve rosin in dibutylphthalate or, I may use ester gum in place of the rosin,—about seventy-five parts of the gum to about twenty-five parts dibutylphthalate, 30 which can be thinned by heating.

Referring now more particularly to Figures 7 to 12 inclusive, it will be observed, especially by reference to the latter figure, that a long strip of card 65 may be prepared in a manner similar 35 to Figures 1 and 2 with a piece of cellulose 66 at one side upon the under face, with an extending marginal portion 67 as shown, and at the opposite side of the strip of card 65 may be provided a strip of labels 68 on the upper face 40 with extending margin 69. This composite sheet may be cut along the line 70, according to the height of the can or container to be made, so that each strip for each container contains the moisture-proof strip 66, 67, which is rolled inside 45 the coil, and the label 68, 69, on the opposite side and opposite face of the strip, forms the outside of the coiled cylinder or body portion of the container to be formed. The free margin 67 is fused to the opposite end 66 by overlapping 50 the same thereupon, and the free end 69 of the label 68 is overlapped upon itself and fastened thereto by suitable adhesion after the wall of the container has been formed. The paper or card 65 may be of any suitable cheap grade of 55 material sufficient for the necessary body and strength of the container, thus forming a cylinder having a non-porous lining with an outer label and, if desired, a piece of colored paper may be laminated between the non-porous strip 66, 67 and the paper 65 to show color therethrough, giving in effect an enameled appearance for the 60 interior of the container, while at the same time minimizing the amount of absorption by the surface to which the film is fastened. Also, it will 65 be readily understood, that the label 68, 69 may be covered with a suitable film of non-porous and transparent material, thus protecting the 70 printing thereon and producing an outer highly polished surface, much superior to ordinary high-class labels. The strips for forming successive cylinders of predetermined length, cut from the composite strip along the line 70, may be supplied in bundles and successively fed to the forming mandrel of the tube-making machine, or

may be fed from the continuous strip and cut off as required for forming into cylinders.

The form of cylinder shown in Figure 7 is provided with a suitable inner lining 71, and an outer label or covering 72, the intervening body 5 of the wall being indicated at 73. A suitable head, covering or end for this container is illustrated in Figure 8, the same being preferably formed of metal such as tin, having an upwardly domed central portion 74, with side wall 75, and base flange 76, preferably terminating in a peripheral inwardly turned portion 77. 78 indicates a disc of non-porous material, and the outer diameter of the wall 75 is very slightly greater than the internal diameter of the body 15 shown in Figure 7, so that as the head and body portion are pressed together, the lower, inner edge 79 of the wall strikes the rounded shoulder 80 of the head or end, carrying the margin of the disc 78 down tightly, squeezing the same 20 against the wall 75, and a suitable solvent having been first applied to the upper marginal surface of the disc 78, or base of the lining 71 and inner wall 73, causes the fusion of the margin of the disc 78 and lining 71 entirely around the container, the same being now in the position shown 25 in Figure 9. The next operation brings the remaining portion of the moistened base flange 76 upwardly, and the peripheral portion 77 is now forced against the outer wall of the container, 30 while at the same time, the wall 75 is now preferably pressed outwardly at the shoulder 80, as indicated at 81, thus slightly restricting the container wall at that point, while the turned portion 77 further restricts it adjacent the same 35 point, thus interlocking the wall of the container to the head, making a secure, immovable fastening, while at the same time providing a continuous, integral, inner lining of non-porous material 40 within the outer body portion of the card of other material, it being understood that a head or end similar to that shown is, of course, applied at the opposite end of the body portion. A removable cap without the restricting elements 77 and 81 may also be so formed, and may be sealed 45 to the container by applying solvent between adjacent faces of the cap lining at 78 and wall lining at 71.

It has been found that this method of moisture-proofing a container is much more economical and certain than by spraying the interior of the container with the non-porous material in liquid form,—first, for the reason that more non-porous material would have to be used as a solution, and the same being usually volatile, further losses occur in that manner, while at the same time, the greater amount of volatile and inflammable material employed increases the fire risk. Furthermore, it has been found extremely difficult to insure a proper uniform distribution of the sprayed material, usually requiring that the paper or cardboard be first treated with a filler, which in turn tends to minimize the adhesion of the sprayed material, due to a minimization of the fibres exposed to be acted upon. Also it has been found practically impossible to properly apply the material at the seams, such as where the head joins the body portion, and necessitates a pre-treatment such as with solvent or sealing agent—at that point between the head lining 70 and the wall lining, whereas, when laminating or covering with pre-formed sheet material, an extremely thin web or film of material may be used, even as thin as a half thousandth of an inch, and being uniformly and thoroughly fas- 75

tened to the inside of the container, has all of the necessary strength and impervious qualities, while at the same time providing a much superior finish and appearance, also lending itself to underlaid sheets, much as for coloring and enameling effects.

In some instances, such as for tobacco or cigar cans, the impervious film may be placed over the label only on the outside of the container, instead of on the inside, and in that case, the inside may be lined with a softer material, such as rough paper, which may be previously soaked in tobacco juice, and the container may be formed while this soft lining is moist with the tobacco juice, so that when the cigars are inserted, and the container is sealed closed, it serves as a humidiifier, sealing the moist air within the container until such time as it is opened. In such case, the impervious coverings applied to the heads or ends of the container would still preferably be on the inside thereof as described, especially where the same are formed of tin, for the purpose of preserving the same from the rusting effect of the moisture, though of course the heads may also be covered externally to form a complete external impervious covering or coating.

The solvent is preferably in fact also a "filler". That is to say, I have found that by using a solvent or adhesive which has also a filler combined therewith, that the moisture-proof properties of the covering or lining are improved, probably for the reason that the cellulose is what might be termed cellular or porous under a microscope, and the filler by filling in the pores or cells of the sheet close them while the solvent fuses the sheet together, or fastens them when some other adhesive is used, the filler being forced into the cells or spaces by the pressure of the rollers during the laminating operation.

In the modification shown in Figures 4 and 5, the can is shown made of a direct or straight convolute winding, in which case a strip of film 88 is provided of a sufficient length to pass completely around the interior of the can to be made, a marginal portion 89 overlapping and fusing to the margin 90, so as to form a complete unitary integral lining or cylinder. To the opposite side of the film 88 is suitably secured an underlining of paper 91 which may be white or any other color and, showing through the film 88 produces an interior enameled effect. This lining paper 91 is backed by filler or card 92, the lining paper and card being of sufficient length according to the number of turns or convolutions intended for the wall of the container. At the outer end or margin 92' of the paper and board strip of label 93 is secured as shown, and at the opposite side a film strip as indicated at 94, so that after the paper and board 91, 92 have been wound, the same is followed by the label 93 covered by the film 94, the end margin 95 of which overlaps the margin at the opposite end, thus providing a container wall or cylinder laminated inside and out with film beneath the inner surface of which is a white or colored paper, and between which and the outer laminated label is provided the board filler.

By reference particularly to Figure 4, it will be observed that when the cylinder wall is rolled in straight convolute manner, the margins 94, 95

of the foregoing outer film will extend above and below the ends of the body of the can. By now moistening the inside of these margins, and turning them inwardly over the top and bottom edges of the can, before pressing a head or heads into the can ends, the top and bottom edges of the can will be covered or sealed, and will not absorb moisture, and the inner and outer film covering of the can will be joined or fused together.

In the modification shown in Figure 6, a composite or laminated strip suitable for straight winding upon a mandrel is shown with parts broken away. 105 indicates the inner lining or film portion, 106 a colored paper thereunder, 107 the board or other body material, 108 the label, and 109 the outer lamination of film with margin 110 for sealing thereto.

Containers made as thus described are preferably filled invertedly, that is, from the bottom, after which the bottom may be readily headed or seamed with a suitable end of paper or metal of either the type seen at 14 or any of the well-known types, as may be desired.

What is claimed as new and is desired to be secured by Letters Patent of the United States is:

1. A paper receptacle having a rolled body portion, the blank of which consists of a strip of body forming paper, a section of moistureproof lining paper secured flatwise upon one surface of said body paper adjacent to one side edge thereof, and a section of wrapper forming paper secured flatwise upon the opposite surface of the body and adjacent to the relatively opposite side thereof.

2. A blank for a rolled paper receptacle consisting of a strip of body forming paper, a section of moistureproof lining paper secured flatwise upon a portion of one surface of said body paper and adjacent to and projecting beyond one side thereof, and a wrapper forming paper secured flatwise upon a portion of the opposite surface of the body paper adjacent to and projecting beyond the relatively opposite side thereof.

3. A blank for a rolled paper receptacle as set forth in claim 2, wherein the projecting portions of the lining and wrapper papers extend in relatively opposite directions around, and are secured over, the opposite side edges of the body paper.

4. A blank for a rolled paper receptacle as set forth in claim 2, wherein a colored opaque paper is secured between the lining paper and the body paper, and wherein the lining paper is transparent.

5. A blank for a rolled paper receptacle as set forth in claim 2, wherein the colored opaque paper extends entirely across the respective surface of the body paper.

6. A blank for a rolled paper receptacle as set forth in claim 2, wherein a transparent protecting sheet is secured flatwise over the obverse face of the wrapper paper.

7. A blank for a rolled paper receptacle as set forth in claim 2, wherein a transparent sheet is secured flatwise to cover the obverse face of the wrapper paper and projects at three sides thereof.
